UNITED STATES PATENT OFFICE.

EUGENE F. McGURK, OF WAUWATOSA, WISCONSIN.

MONEY-WRAPPER.

1,333,087.

Specification of Letters Patent. Patented Mar. 9, 1920.

Application filed January 19, 1919. Serial No. 270,509.

To all whom it may concern:

Be it known that I, EUGENE F. McGURK, a citizen of the United States, and resident of Wauwatosa, in the county of Milwaukee, 5 and State of Wisconsin, have invented new and useful Improvements in Money-Wrap-
pers, of which the following is a description, reference being had to the accompanying drawings, which are a part of this specifica-
tion.

The invention relates to money wrappers for securing money of different denomina-
tions in packages.

So far as I am aware it has been the practice up to this time to provide a special wrapper or strap for each denomination of coin or amount of currency and it is the object of this invention to provide a simple form of wrapper or strap which may be used for several denominations of different amounts, thus saving time, labor and expense in connection with banking business.

The invention further consists in the several features hereinafter described and shown in the accompanying drawings in which:

Figure 1 is a view of one of the wrappers embodying the invention;

Fig. 2 is a view of the other side of the wrapper;

Fig. 3 is a view of one side of a modified form of wrapper embodying the invention;

Fig. 4 is a view of the other side of a modified form of wrapper embodying the invention;

Fig. 5 is a view of the wrapper shown in Figs. 3 and 4, folded on the dotted line of Fig. 4;

Fig. 6 is a perspective view of a package of wrapped coin;

Fig. 7 is a view of one side of a currency strap embodying the invention;

Fig. 8 is a view of the other side of the strap; and

Fig. 9 is a view of the strap applied to currency.

Referring to Figs. 1 and 2, the numeral 7 designates the wrapper which is formed of a single blank of paper or other suitable material having printed matter on its sides 8 and 9. At one end 10 on the side 8 there appears printed matter designating a cer-
tain denomination of coin as "20 dollars silver" and at the other end 11 of the side 8 there appears printed matter designating another denomination of coin as "50 cents

pennies." In the intermediate portion of this side are directions 12 readable from opposite ends of the slip, reading "Wrap nickels from this end" with an arrow 14 60 pointing to the end from which the wrap-
ping is started, and "Wrap quarters from this end" with an arrow 13 pointing to the end from which the wrapping is started. At one end 15 of the side 9 there appears 65 printed matter designating another denomina-
tion of coin as "2.00 nickels" and at the other end 16 of this side there appears printed matter designating another denomina-
tion of coin as "10 dollars quarters." In 70 the intermediate portion of this side of the slip or blank are directions 17 readable from opposite ends of the slip, reading "Wrap silver dols. from this end" and "Wrap pen-
nies from this end" with arrows 18 and 19 75 designating the end upon which the wrap-
ping is to be started.

With this construction if it is desired to wrap two dollars in nickels, the nickels to this amount are arranged in line trans- 80 versely of and near the end 11 of the side 8 of the slip in accordance with the instruc-
tions, "Wrap nickels from this end" and the arrow 14 and said nickels are then wrapped up and the side edges of the wrapper folded 85 in as shown in Fig. 6 with the result that the words "2.00 nickels" appear on the package. In this way the other denomina-
tions of coin which this wrapper takes may be wrapped up, the filled wrapper designat- 90 ing just what coin is contained therein. While I have shown the use of a wrapper for four denominations the wrapper may be used for two denominations where the different denominations are wrapped up from 95 opposite ends of the same side of the slip or from the same ends of opposite sides of the slip, or from opposite ends of opposite sides of the slip, and that the wrapper may also be used for taking care of three denom- 100inations of coin.

Referring to Figs. 3 to 5 inclusive the wrapper in this case can be used for six different denominations of coin. Upon the side 20 of the slip there appears printed coin 105 denominations 21 and 22 and directions 23 intermediate the slip similar to those of Fig. 1 with the designating arrows 24 and 25. Upon the other side 26 of the slip there ap-
pears printed coin denominations 27 and 28 at the ends of the slip, printed coin de-
nominations 29 and 30 intermediate the ends

- and directions 30 and 31 for wrapping between the matter 27 and 29 and 28 and 30 respectively and a dotted line 32 is printed on this side to indicate the line of fold. 5
5 With this construction the wrapper may be used full length for silver dollars, halves, nickels, and quarters by following the directions for wrapping appearing thereon, or the slip may be folded as shown in Fig. 5
10 and used for pennies and dimes.

Referring to Figs. 7 to 9 inclusive the currency strap is formed of a single blank of paper or other suitable material having printed matter on its sides 33 and 34. At 15 one end of the side 33 there appears printed matter designating the amount and the denomination of currency as "300—5—10—20" in which the "300" repeated designates the amount and either the 5 or 10 or 20 is 20 checked to designate the kind of currency inclosed by the strap to make up this amount. Similarly the other end of this side has 50 repeated and "1—2". At the ends of this side of the strap are directions 25 35 and 36 for wrapping the currency. At one end of the side 34 there appears printed matter designating the amount and the denomination of the currency as "200" and "5—10—20" which is to be checked by 30 the party making up the package and at the other end "500" and "5—10—20" with directions 37 and 38 for wrapping the currency. With this construction, if it is desired to wrap 5 dollar bills to the amount 35 of 500 dollars, the bills are placed on the side 33 and the ends brought together to display the numerals "500" and the numeral "5" underneath is checked and the ends of the strap secured together by sticker 39 which 40 may have printed matter 40 thereon designating the name of the bank which has made up the package as shown in Fig. 9.

What I claim as my invention is:

1. A wrapper of the class described having 45 money denomination indicating designations at the ends thereof and whereby the wrapper may be employed for money of dif-

ferent denominations by wrapping money of one denomination from one end of the opposite side or from the other end of the 50 opposite side to display the denomination of money contained within the wrapper, and directions thereon for wrapping.

2. A money wrapper having denomination and amount indicating designations at 55 the ends thereof on both of its sides whereby the wrapping of money of different amounts and denomination from different ends of the wrapper will display the denomination and amount contained within 60 the wrapper.

3. A coin wrapper having coin indicating designations at the ends thereof on one of its sides whereby the wrapper may be employed for coin of different denominations 65 by wrapping coin of one denomination from one end of the opposite side or from the other end of the opposite side to display the designation of coin contained within the wrapper. 70

4. A coin wrapper having coin indicating designations on opposite sides whereby the wrapper may be employed for coin of different denominations by wrapping the coin from one end of the opposite side upon 75 which the designation of the coin contained within the wrapper appears to display on the outside of the package the designation of the kind of coin contained therein.

5. A coin wrapper for use on a plurality 80 of coins of different denominations provided with denomination and amount indicating designations at its ends and intermediate its ends whereby the wrapping of coin of one denomination in the full wrapper, the coin 85 of that designation will appear on the outside of the wrapper and whereby on the folding of the wrapper and the wrapping of a coin of different denomination therein will display the designation of this coin on 90 the outside of the wrapper.

In testimony whereof I affix my signature.

EUGENE F. McGURK.
